UNITED STATES PATENT OFFICE.

DANIEL R. SCHOLES, OF CHICAGO, ILLINOIS, ASSIGNOR TO AERMOTOR COMPANY, OF CHICAGO, ILLINOIS, A CORPORATION OF ILLINOIS.

TRANSMISSION-TOWER.

No. 821,126.

Specification of Letters Patent.

Patented May 22, 1906.

Application filed February 21, 1906. Serial No. 302,226.

To all whom it may concern:

Be it known that I, DANIEL R. SCHOLES, a citizen of the United States, residing at Chicago, in the county of Cook and State of Illinois, have invented new and useful Improvements in Transmission-Towers, of which the following is a full, clear, concise, and exact description, reference being had to the accompanying drawings, forming a part of this specification.

My invention relates to improvements in skeleton towers or built-up towers of structural iron.

My tower is particularly designed for supporting electrical transmission-wires, although the same may be applied to various other purposes, if so desired.

One object of my invention is to provide a tower which is so constructed that the lateral strain of the transmission-wires shall be brought upon the guy-wires of the tower rather than upon the framework thereof, thereby preventing twisting and distortion of the tower.

Structural towers which have ordinarily been used for carrying transmission-wires have been so constructed that in event of any additional lateral strain—as, for instance, the breaking of one of the wires or the falling across the wires of trees, &c.—being brought upon the cross-arms carrying the wires the strain will tend to twist either the cross-arms or the entire tower.

In accordance with my present invention I preferably connect the guy-wires of the tower to the outer ends of the cross-arms, which are so constructed that they shall have enough flexibility to permit them when strain is brought upon the ends of the arms to give sufficiently to take up the slack of the guy-wire, whereby the strain is taken by the guy-wire instead of by the tower or cross-arms, and twisting of these parts is prevented.

I have illustrated one form of my invention in the accompanying drawings, in which—

Figure 1 is a side elevation of the upper portion of my tower. Fig. 2 is an end elevation thereof. Fig. 3 is a plan view of one of the cross-arms of my tower, and Figs. 4 and 5 are detail views of portions of the cross-arms.

In the preferred embodiment of my invention the top of my tower is constructed of

four converging posts 1, which are preferably formed of angle-iron. At suitable intervals on these posts diagonal braces 2 and cross-braces 3 are connected to the posts in such a manner that the same shall be braced and the tower given great strength and rigidity. The converging upper ends of the posts of the tower are suitably clamped together about a vertical post 4, the lower end of which is secured in a support 5, mounted between the posts of the tower, and the upper end of which fits into a socket on a cast cross-arm 6, provided also with sockets at its outer ends, in which are arranged to be secured insulator-pins 7 for carrying transmission-wires.

A second cross-arm is secured at a lower point on the tower and comprises a pair of parallel angle-pieces 8, the outer ends of which are connected by cross-pieces 9. These cross-arms have preferably formed at their outer ends integrally-formed angle-sockets 10, in which the ends of the angle-pieces forming the parallel members of the cross-arms are arranged to be secured. Sockets are also formed in these connecting cross-pieces, in which are fitted insulating-pins 11 for carrying the transmission-wires. Downwardly-extending angle-sockets 12, which are diagonally arranged, are also formed integrally with the cross-arms, and the upper ends of diagonal braces 13 are arranged to be bolted or otherwise secured to these angle-sockets. The lower ends of these diagonal braces 13 converge and are suitably bolted or otherwise secured to a horizontal brace 14 of the tower. Lugs 15, integrally formed with the cross-pieces, are provided with eyes 16, in which are arranged to be secured the ends of guy-wires 17, the lower ends of which are arranged to be anchored in the ground.

By the above construction of cross-arms sufficient lateral resiliency is given thereto whereby in event lateral strain is brought upon the transmission-wires the arms will give sufficiently to take up the slack of the guy-wires and the strain will be taken by the guy-wires instead of by the cross-arm of the tower, thus preventing all twisting and distorting of the tower.

In order to more fully illustrate the manner of operation of my tower, it will be assumed that the strain upon the transmission-wire occurs in the direction of the arrow. In

such an event the cross-arm will give sufficiently to permit the slack to the guy-wire to be taken up, and the strain will be taken by the guy-wires.

5 Having thus described my invention, what I claim as new, and desire to secure by Letters Patent, is—

1. A tower having a resilient cross-arm, the guy-wires of said tower being secured to 10 said arm.

2. A skeleton tower having a resilient cross-arm, the guy-wires of said tower being secured to the ends of said arm.

3. The combination with a skeleton tower, 15 of a cross-arm therefor, comprising angle-irons secured upon either side of the tower, means for connecting the ends of said angle-irons together, and guy-wires for said tower connected at the outer ends of said arm, 20 said arm being resilient to permit a lateral movement thereof, whereby the lateral strain upon the same will be taken up by said guy-wires.

4. The combination with a skeleton tower, 25 of a cross-arm therefor, comprising angle-irons secured upon each side of the tower, means for connecting the outer ends of said angle-irons together, wire-supporting pins carrying means at the outer ends of said 30 cross-arm and guy-wires for said tower connected to the outer ends of said arm, said

arm being resilient to permit a lateral movement thereof, whereby the lateral strain upon the arms will be taken up by said guy-wires.

5. The combination with a skeleton tower, 35 of a cross-arm therefor, guy-wires secured to the outer ends of said cross-arm, and diagonal supports connected at one end to the outer end of said cross-arm, and at the other end to the tower, said cross-arm being resilient to permit a lateral movement thereof. 40

6. The combination with a skeleton tower, of a cross-arm therefor, comprising angle-irons arranged upon each side of said tower, means for connecting the outer ends of said 45 angle-irons, insulator-pins carried upon the outer ends of said cross-arm, and braces for said cross-arm comprising angle-irons connected at their upper ends to said cross-arm and converging toward their lower ends and 50 connected to said tower, and guy-wires connected at the outer ends of said cross-arm, said arm being resilient to permit of a lateral movement thereof.

In witness whereof I have hereunto subscribed my name in the presence of two witnesses.

DANIEL R. SCHOLES.
